SPRING CONSTRUCTION

Alexander W. Moske, Jackson, Mich., assignor to
 Reynolds Spring Company, Jackson, Mich., a
 corporation of Delaware

Application October 17, 1940, Serial No. 361,501

5 Claims. (Cl. 155—179)

The present invention relates to automobile seat cushion springs and more particularly to cushion springs comprised of a plurality of spiral springs disposed on end side by side.

Automobile seat cushion springs composed of spiral springs in parallel rows side by side generally have the top coils thereof connected together by pig rings so as to provide a flexible but substantially non-extensible surface. The result is that when a load is placed on the cushion, as for instance, a person sitting thereon, and the cushion is deflected inwardly, the inextensibility of the top surface results in the border of the cushion being drawn inwardly. According to the present invention the top coils of the springs are connected together in such a manner as to be slightly displaceable with respect to each other, whereby the cushion is made softer not only because there is not a general distortion of the frame of the cushion due to the inextensibility of the top thereof, but also because the individual spiral springs are permitted to act individually, thereby more readily conforming to the shape of the person sitting thereon.

An object of the invention is to provide a seat cushion spring comprised of spiral springs on end, supported in a border frame, having a top surface composed of a plurality of top coils of the helical springs fastened together in such a manner as to permit relative displacement, whereby the individual coils are provided with a greater freedom of individual action.

Another object of the invention is to provide a seat cushion spring comprised of a plurality of spiral springs having the top coils thereof substantially disposed in a general plane and pig ringed together in such a manner as to permit lateral displacement of the said coils with respect to each other to permit relative freedom of individual action of the springs.

These and other objects residing in the arrangement, combination and construction of the parts will be apparent from the following specification when taken with the accompanying drawing, in which:

Fig. 1 is an elevation of a cushion spring construction without the upholstering thereon illustrating the invention, and

Fig. 2 is an enlarged portion of Fig. 1, showing the details thereof.

The reference character 1 indicates a border wire frame of conventional construction within which are disposed a plurality of spiral springs 2 arranged in laterally extending rows. The springs 2 are en-

cased in fabric pockets 3 and are known in the art as being of the Marshall type.

In the drawing, the top of Fig. 1 represents the rear of the cushion, and the bottom of Fig. 1 represents the front of the cushion. Immediately in front of the rear row of springs 2 which are fabric covered is a row of bare springs 4. In front of the row of bare springs 4 is another row of fabric covered springs 2 and between this row of fabric covered springs 2 and the rear row of the front three rows of fabric covered springs 2 is another row of bare springs 4. It will be observed from the drawing that the bare springs 4 are in nested relation with the fabric covered springs 2, and that the fabric covered springs 2 extend laterally in each direction into contact with the sides of the frame 1. The rows of springs 4, however, start inwardly from the sides of the frame 1 due to their nested relation with the springs 2. It is preferred that the springs 2 within the fabric pockets 3 be of cylindrical form and that the springs 4 be of hour-glass form. However, this arrangement is not essential to the invention. Furthermore, while it has been found desirable to have the springs 2 slightly larger in diameter than the springs 4, this arrangement is not an essential feature of the invention.

It will be understood by those skilled in the art that the frame 1 is in generally rectangular outline and may lie within a single plane or may be slightly curved from front to back, depending on the exact seat construction desired. However, generally, the frame 1 is flat and the top coils of the springs 2 and 4 lie within the general plane thereof, the contour of the finished seat being provided by padding and upholstering covering the same. The lower ends of the springs 2 are disposed in a lower frame structure, not shown, and are supported with respect thereto in a conventional manner. Also in a conventional manner the top and bottom frame portions are braced with respect to each other.

The top coils of the springs 2 and 4 are disposed in substantially tangential relation to each other and to the border wire 1 as shown. Pig rings 5 are employed to connect the top coils of the border springs 2 to the border wire 1 and pig rings 6 are employed to connect adjacent top coils of the springs 2 and 4 together, at the points they tangentially engage. An important feature of the invention is the fact that the springs 2 are spaced laterally substantially more than they are spaced from front to back.

In conventional spring constructions, wherein

all of the coil springs are in rows both laterally and from front to back, as shown for instance in Patent No. 2,002,158, a load placed on the top of the springs, such as a person sitting thereon, will cause the top surface of the cushion structure to be deflected downwardly. Since each of the top coils of the cushion springs are connected rigidly together both laterally and from front to rear, the downward deflection of the top surface will result in an inward deflection of the border frame. Such an inward deflection is particularly undesirable as it occurs for the most part along the front edge of the seat and not only tends to pull the front of the seat out of shape, but also the inextensibility of the top surface prevents the individual functioning of the springs of the cushion construction.

In the use of the spring structure, according to the present invention, when a person places his weight on the top of the construction, the connection between the front and back frame portions extends due to the fact that the pig rings 6 slide along top coils of the bare springs 4. This sliding action has the effect of providing a slack in the connection between the front and back portions of the border frame 1, with the result that the downward displacement of any part of the top of the spring structure has less of a tendency to deflect the border wire 1 inwardly than would be the case if there were no slack or extensibility provided. Thus, for a given load on the seat structure, the frame 1, which due to the shape thereof and placement of the load, is usually bowed inwardly in the front, has its shape preserved or altered only slightly. Consequently, the top surface of the spring structure will sink lower under a given load, thereby having a softer cushioning action. Also, since there is an effective slack between the top coils of the springs 2 and 4, the springs 2 and 4 are given a greater freedom of individual action than would be possible for example in the conventional prior art structures wherein there is a straight line connection between the top coils of the springs of the structure and the border frame. As a result the spring structure is more comfortable because it more readily conforms to the shape of a person sitting thereon.

The springs 2 are spaced laterally a greater distance than from front to back in order to favor extensibility in a direction from front to back, since the front to back dimension of the cushion spring structure is less than the lateral dimension thereof, and therefore a load placed on the top of the structure is more likely to result in a deflection of the front border or rear border of the seat cushion than the side borders. In the preferred arrangement shown with only two rows of nested bare springs 4, arranged toward the rear portion of the seat cushion construction, the region of extensibility is located at the portion of the seat cushion construction which normally receives the concentrated load in use. Nevertheless, it will be understood that the bare springs 4 may be placed in alternate rows throughout the entire cushion structure from front to back if desired without departing from the spirit of the invention.

From the foregoing specification, it will be apparent that there are other advantages than those enumerated therein. For instance, since the bare springs 4 are placed in alternate rows there is a saving in fabric pockets 3, and at the same time, no adjacent bare springs which might result in metal to metal contact with resulting noise dur-

ing operation. Furthermore, the nested relation of the bare springs 4 results in a savings in the number of springs required, since there is a saving of one spring for each row of bare springs 4 over a conventional construction wherein all of the springs are side by side from front to back and laterally.

Having thus described my invention, what I desire to secure by Letters Patent and claim is:

- 10 1. In an automobile seat cushion spring, a generally rectangular top border frame, a plurality of laterally extending rows of spiral springs disposed on end within said border frame and encased in fabric pockets, a plurality of laterally extending rows of bare spiral springs disposed on end within said border frame, said rows of bare spiral springs being alternated with certain rows of fabric encased springs, the outer rows of springs being encased, the springs of said bare rows of springs being in nested relation to the springs of said fabric encased rows of springs, said fabric encased springs being spaced laterally a greater distance than from front to back, all of said springs having top coils disposed under normal conditions substantially in a general plane, said top coils being in substantial tangential engagement with one and another, pig rings connecting said top coils together at adjacent points, and pig rings connecting border coils to said border frame, said pig ring connected coils providing a surface constituting an extensible connection between opposite sides of said frame, said connection being extensible due to the sliding of certain of said pig rings on the bare top coils when a load is placed on the top of said top coils, whereby when a load is placed on said top coils, each spring is provided with a greater freedom of individual action than would be obtained if all the coils were pig ringed together in a straight line normal to the sides of said border frame.
- 20 2. In an automobile seat cushion spring, a generally rectangular top border frame, a plurality of laterally extending rows of spiral springs disposed on end within said border frame, a plurality of laterally extending rows of supplementary spiral springs disposed on end within said border frame, said rows of supplementary springs being alternated with certain rows of said first named springs, the springs of said supplementary rows of springs being in nested relation to said first named springs, said first named springs being spaced laterally a greater distance than from front to back, all of said springs having top coils disposed under normal conditions substantially in a general plane, said top coils being in substantial tangential engagement with one another, pig rings connecting said top coils together at adjacent points, and pig rings connecting border coils to said border frame, said pig ring connected coils providing a surface constituting an extensible connection between opposite sides of said frame, said connection being extensible due to the sliding of certain of said pig rings on the supplementary top coils when the load is placed on the top of said top coils, whereby when a load is placed on said top coils each spring is provided with a greater freedom of individual action than would be obtained if all the coils were pig ringed together in a straight line normal to the sides of said border frame.
- 30 3. In an automobile seat cushion spring, a generally rectangular top border frame, a plurality of laterally extending rows of spiral springs disposed on end within said border frame, a plurality of laterally extending rows of reduced di-

- 75

ameter spiral springs disposed on end within said border frame, said rows of reduced diameter springs being alternated with certain rows of said first named springs, the springs of said reduced diameter rows of springs being in nested relation to said first named springs, said first named springs being spaced laterally a greater distance than from front to back, all of said springs having top coils disposed under normal conditions substantially in a general plane, said top coils being in substantial tangential engagement with one another, pig rings connecting said top coils together at adjacent points, and pig rings connecting border coils to said border frame, said pig ring connected coils providing a surface constituting an extensible connection between opposite sides of said frame, said connection being extensible due to the sliding of certain of said pig rings on the supplementary top coils when the load is placed on the top of said top coils, whereby when a load is placed on said top coils each spring is provided with a greater freedom of individual action than would be obtained if all the coils were pig ringed together in a straight line normal to the sides of said border frame.

4. In an automobile seat cushion spring, a generally rectangular top border frame, a plurality of laterally extending rows of spiral springs disposed on end within said border frame, a plurality of laterally extending rows of supplementary spiral springs disposed on end within said border frame, said rows of supplementary springs being alternated with certain rows of said first named springs, the springs of said supplementary rows of springs being in nested relation to said first named springs, said first named springs being spaced laterally a greater distance than from front to back, all of said springs having top coils disposed under normal conditions substantially in a general plane, said top coils being in substantial tangential engagement with one another, fabric pockets encasing at least the springs of said first named rows of springs adjacent said supplementary springs, pig rings connecting said top coils together at adjacent points, and pig rings con-

necting border coils to said border frame, said pig ring connected coils providing a surface constituting an extensible connection between opposite sides of said frame, said connection being extensible due to the sliding of certain of said pig rings on the supplementary top coils when the load is placed on the top of said top coils, whereby when a load is placed on said top coils each spring is provided with a greater freedom of individual action than would be obtained if all the coils were pig ringed together in a straight line normal to the sides of said border frame.

5. In an automobile seat cushion spring, a generally rectangular top border frame, a plurality of laterally extending rows of spiral springs disposed on end within said border frame, a plurality of laterally extending rows of reduced diameter spiral springs disposed on end within said border frame, said rows of reduced diameter springs being alternated with certain rows of said first named springs, the springs of said reduced diameter rows of springs being in nested relation to said first named springs, said first named springs being spaced laterally a greater distance than from front to back, all of said springs having top coils disposed under normal conditions substantially in a general plane, said top coils being in substantial tangential engagement with one another, fabric pockets encasing at least the springs of said first named rows of springs adjacent said reduced diameter springs, pig rings connecting said top coils together at adjacent points, and pig rings connecting border coils to said border frame, said pig ring connected coils providing a surface constituting an extensible connection between opposite sides of said frame, said connection being extensible due to the sliding of certain of said pig rings on the reduced diameter top coils when the load is placed on the top of said top coils, whereby when a load is placed on said top coils each spring is provided with a greater freedom of individual action than would be obtained if all the coils were pig ringed together in a straight line normal to the sides of said border frame.
